[57] CLAIM

The ornamental design for a watch box, as shown and described.

DESCRIPTION

FIG. 1 is a top plan view of a watch box showing my new design, the ornamentation shown being embossed on the under surface of the cover;
FIG. 2 is a front elevational view on a reduced scale;
FIG. 3 is a side elevational view thereof;
FIG. 4 is a rear elevational view thereof; and
FIG. 5 is a bottom plan view thereof.
